ATTORNEY

UNITED STATES PATENT OFFICE.

GEORGE BASCOMB WELDON, OF PITTSBURGH, PENNSYLVANIA.

ATTACHMENT FOR FINGER-BOWLS.

1,123,937.

Specification of Letters Patent.

Patented Jan. 6, 1915.

Application filed April 13, 1914. Serial No. 337,372.

To all whom it may concern:
Be it known that I, GEORGE BASCOMB WELDON, a citizen of the United States of America, residing at Pittsburgh, in the county of Allegheny and State of Pennsylvania, have invented certain new and useful Improvements in Attachments for Finger-Bowls, of which the following is a specification, reference being had therein to the accompanying drawing.

This invention relates to attachments for finger bowls, and has for its object to provide an attachment for use in connection with finger bowls to prevent employing water which has been previously used for cleansing the fingers.

Further objects of the invention are to provide an attachment for the purpose set forth which is simple in its construction and arrangement, efficient and convenient in its use, readily set up with respect to the body of the bowl and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings, wherein like reference characters denote corresponding parts throughout the several views: Figure 1 is a top plan view of an attachment for finger bowls in accordance with this invention, and Fig. 2 is a cross sectional view of a finger bowl, showing the adaptation thereof with of an attachment in accordance with this invention.

Referring to the drawings in detail, 3 denotes the body of a finger bowl and 4 the bottom, and extended within the bowl is a tapering member 5, provided with a flange 6, which overlaps the top edge 7 of the body 3, whereby the member 5 is suspended with-

in the bowl 3 above the bottom thereof. The tapering member 5 includes a flat bottom 8, which is connected in position by wax or other suitable means 9, to enable the bottom to be conveniently separated from the bottom 5, as illustrated in dotted lines Fig. 2. The member 5 is preferably constructed of paper and is adapted to contain a body of water as indicated at 10.

After one has cleansed his fingers in the water 10 the bottom 8 is quickly severed or detached from the body 5 by exerting pressure thereon and the water will fall into the body 3 of the bowl. The bowl is served only with a member 5, containing a body of water, and by such an arrangement it is obvious that when the bottom 8 is severed one will not be able to use the water which has been previously employed for cleansing the fingers.

What I claim is:

1. An attachment for finger bowls comprising a flanged wafer holding member adapted to be suspended in the body of a finger bowl and having a bottom detachably connected in position.

2. An attachment for finger bowls comprising a tapering water holding member provided with a flange seating upon the top edge of a finger bowl whereby said member is suspended within the bowl, said member further including a detachable bottom.

3. An attachment for finger bowls comprising a tapering water holding member provided with a flange seating upon the top edge of a finger bowl whereby said member is suspended within the bowl, and said member further including a disk arranged therein and detachably connected therewith and constituting a bottom therefor.

In testimony whereof I affix my signature in the presence of two witnesses.

GEORGE BASCOMB WELDON.
